CLAIM

The ornamental design for a wall mountable door access device, as shown and described.

DESCRIPTION

FIG. 1 is a front view of a wall mountable door access device showing our new design;

FIG. 2 is a right-side view of the wall mountable door access device shown in FIG. 1;

FIG. 3 is a rear view of the wall mountable door access device shown in FIG. 1;

FIG. 4 is a top view of the wall mountable door access device shown in FIG. 1;

FIG. 5 is a left-side view of the wall mountable door access device shown in FIG. 1;

FIG. 6 is a bottom view of the wall mountable door access device shown in FIG. 1; and,

FIG. 7 is a top front perspective view of the wall mountable door access device shown in FIG. 1.

The broken lines of FIGS. 3 and 6 are provided for purposes of illustrating portions of the wall mountable door access device that form no part of the claimed design. Surfaces encircled in broken line form no part of the claimed design.

1 Claim, 7 Drawing Sheets
